UNITED STATES PATENT OFFICE

114,606

DESIGN FOR A SHOE

Burton L. Wales, Abington, Mass., assignor to The Stetson Shoe Company, Incorporated, Weymouth, Mass., a corporation of Massachusetts

Application December 19, 1938, Serial No. 81,867

Term of patent 3½ years

To all whom it may concern:

Be it known that I, Burton L. Wales, a citizen of the United States of America and a resident of Abington, in the county of Plymouth, Commonwealth of Massachusetts, have invented a new, original, and ornamental Design for Shoes, of which the following is a specification, reference being had to the accompanying drawing, forming part thereof.

In the drawing:

Fig. 1 is a plan view of a shoe, showing my new design, and

Fig. 2 is a side elevation.

Applicant's design consists in the combination of the moccasin front, the distinctive cut of the side portions, the tie string extending around the top, and the heel, substantially as shown.

I claim:

The ornamental design for a shoe, substantially as shown and described.

BURTON L. WALES.
